(57) **CLAIM**

The ornamental design for a wireless patient monitoring device, as shown and described.

DESCRIPTION

FIG. 1 is a bottom, front, left-side perspective view of a wireless patient monitoring device embodying our design in a first environment;

FIG. 2 is a front elevation view thereof in a second environment;

FIG. 3 is a partial, top, front, right-side perspective view thereof in a different position in the second environment; and,

FIG. 4 is partial, top, front, right-side perspective view thereof in still another different position in the second environment.

The broken lines depicting the outlet and the rear surface of the wireless patient monitoring device illustrate portions that form no part of the claimed design, while all other broken lines are directed to environmental structures and are for illustrative purposes only. The broken lines form no part of the claimed design.
